CLAIM

The ornamental design for a blister pack, as shown and described.

DESCRIPTION

This application claims priority to patent application No. 8876201, registration No. DM/102854, filed with the International Bureau on Sep. 12, 2018 and it is hereby incorporated herein by reference in its entirety.

FIG. 1 is a perspective view of a blister pack embodying our new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a perspective view of a second embodiment of a blister pack embodying our new design;

FIG. 9 is a front view thereof;

FIG. 10 is a back view thereof;

FIG. 11 is a left view thereof;

FIG. 12 is a right view thereof;

FIG. 13 is a top view thereof; and,

FIG. 14 is a bottom view thereof.

Any broken lines shown in the drawings are for illustrative purposes only and form no part of the claimed design.

1 Claim, 14 Drawing Sheets
